WINDOW REGULATOR

Henry W. Mackey, Detroit, Mich., assignor to
 Motor Products Corporation, Detroit, Mich., a
 corporation of New York

Application May 2, 1938, Serial No. 205,551

3 Claims. (Cl. 268—126)

This invention relates generally to window regulators of the type employed to raise and lower glass panels provided in the window openings of vehicle bodies.

One of the principal objects of this invention is to provide a window regulator composed of a relatively few simple parts capable of being inexpensively manufactured and cooperating when assembled to permit raising and lowering the window with the minimum effort. In accordance with this invention, the effort required to raise or lower the window is reduced to the minimum by providing a window regulator so constructed that the thrust and pull on the window is in the form of a vertical line thrust applied substantially at the center of the window. As a result, there is no tendency for the window to tilt during the movement thereof and cause undue friction against the window guides.

Another advantageous feature of the present invention resides in the provision of a window regulator of the character set forth embodying means effective to shift the window transversely to the direction of sliding movement thereof as the same approaches its uppermost position in the window opening and during initial movement of the window downwardly relative to the window opening.

The foregoing, as well as other objects, will be made more apparent as this description proceeds, especially when considered in connection with the accompanying drawings; wherein

Figure 1 is an inside view of a portion of a vehicle body having a window opening therethrough and having a sliding closure panel operated by a window regulator constructed in accordance with this invention;

Figure 2 is an enlarged side elevational view of the window regulator shown in Figure 1;

Figure 3 is a sectional elevational view taken substantially on the plane indicated by the line 3—3 of Figure 2;

Figure 4 is a sectional view taken substantially on the plane indicated by the line 4—4 of Figure 2;

Figure 5 is a cross sectional view taken substantially on the plane indicated by the line 5—5 of Figure 2;

Figure 6 is a cross sectional view taken on the line 6—6 of Figure 2;

Figure 7 is a sectional view taken on the line 7—7 of Figure 2;

Figure 8 is a sectional view taken on the line 8—8 of Figure 2;

Figure 9 is a cross sectional view taken on the line 9—9 of Figure 1;

Figure 10 is a view similar to Figure 1 showing a slightly modified form of the invention; and

Figure 11 is a cross sectional view taken on the plane indicated by the line 11—11 of Figure 10.

For the purpose of illustrating the present invention, I have selected a composite window of the ventilating type embodying a swinging panel and a vertically sliding panel cooperating with the swinging panel in the raised position thereof to close the window opening in the vehicle body. However, it will be understood from the following description that the present invention is by no means limited to the above construction of the window and that my improved regulator is applicable in any case where it is desired to effect raising and lowering of the window panel.

Referring now more in detail to the drawings, it will be noted that there is illustrated in Figure 1 a portion of a vehicle body having a window opening 10 and having a closure 11 for the window opening. As stated above, the closure 11 is in the form of a ventilating window having a vertically slidable glass panel 12 and having a pivoted panel 13 mounted in the window opening in advance of the panel 12 to cooperate with the latter in the uppermost position of the same to completely close the window opening. In accordance with the conventional practice, the panel 13 is pivotally supported in the window opening for swinging movement about a substantially vertical axis located between the front and rear edges of the panel. The general arrangement is such that when the panel 13 is swung to an open position, the portion of the panel in advance of the vertical axis moves inwardly with respect to the plane of the window opening and the portion of the panel in rear of the axis moves outwardly with reference to said plane. As a result, air is drawn into the vehicle through the opening provided at the forward end of the panel 13 and is exhausted from the vehicle through the slot existing at the rear edge of the panel 13.

In the closed positions of both panels in the window opening, the space between the adjacent edges of the panel is sealed by means of a division bar 14 having the additional function of forming an abutment for engaging the rear vertical edge of the swinging panel to locate the latter in its closed position. The division bar 14 is fashioned to have the cross sectional contour shown in Figure 5 and may be secured to either one of the adjacent edges of the two window panels. In the present instance, the division bar is shown as se-

cured to the forward vertical edge of the sliding panel 12 and for this purpose is formed with a rearwardly opening longitudinal extending channel 15 receiving the forward edge of the sliding panel 12. As stated above, the division bar also forms an abutment for the rear edge of the pivoted panel 13 and, for accomplishing this result, the division bar is provided with a longitudinally extending forwardly projecting flange 16 at the outer edge thereof. A suitable sealing strip 17 is secured to the forward edge of the division bar in the manner shown in Figure 5 to engage the rear edge of the panel 13 and provide a seal for said edge.

15 The panel 12 is mounted for vertical sliding movement from a position within the window opening to a position within the usual compartment or well 18 provided by the inner and outer panels of the body below the window opening. 20 In the specific embodiment of the invention selected for the purpose of illustration, the rear edge of the panel 12 slides in a channel-shaped runway 19 suitably secured to the body and having a portion 20 extending forwardly along the 25 upper side of the window opening for receiving the top edge of the panel 12 when the latter is in its closed or uppermost position.

The panel 12 is moved between the two positions mentioned above by means of a window regulator, designated in the several figures of the drawings by the reference character 21. The regulator is so constructed that the thrust and pull on the window is in the form of a vertical line thrust applied at the bottom edge of the 30 window substantially midway between the front and rear edges of the latter. In detail, the window regulating mechanism comprises a T-shaped arm 22 having the stem portion 23 extending in the direction of sliding movement of 35 the panel 12 substantially midway between the front and rear edges of the latter panel. The transverse section 24 of the T at the upper end of the stem 23 extends parallel to the bottom edge of the panel 12 and is offset outwardly with respect to the window opening at opposite ends to 40 form attaching lugs 25. The attaching lugs 25 are secured to the bottom longitudinal edge portion 26 of a channel 27 by means of the fastener elements 28, and the channel 27 is, in turn, 45 secured to the bottom edge of the glass panel 12 in the usual manner.

A follower or pin 29 is secured to the lower end of the stem portion 23 on the T-shaped arm in a manner to extend inwardly from the arm 55 and cooperate with a track 30 to guide the arm throughout its vertical movement. The track 30 is in the form of an outwardly opening channel-shaped section having a base portion 31 secured intermediate the ends to the regulator supporting plate 32 and having the lower end secured to the body structure in the window well 18. Upon reference to Figure 8, it will be noted that the free longitudinal edge portions of the flanges 33 on the track are bent laterally inwardly toward the vertical center line of the channel to provide longitudinally extending beads 34 for engagement with the inner end of the pin 29. In this connection, it will be noted that the inner end of the pin 29 is provided with an enlarged 60 head 35 located in the channel of the track and having a diameter greater than the width of the slot between the beads 34 so as to prevent lateral displacement of the pin out of the channel. It will, of course, be understood that the 65 opposite ends of the channel-shaped track are

open to permit assembling the pin with the track from either end of the latter. It will also be noted from Figure 8 that the head 35 on the pin is held into frictional engagement with the beads 34 on the track to prevent rattling of the 5 parts by means of a washer 36 slidably mounted on the pin 29 at the outer side of the track 30 and having a frusto-conical surface urged into wedging engagement with the free edges of the flanges 33 on the track by means of a spring 37. 10 The spring 37 encircles the pin 29 with one end engaging the washer 36 and with the opposite end engaging the arm.

For the purpose of raising and lowering the arm 22 to effect a corresponding movement of the panel 12, I provide reduction gearing 38 mounted on the plate 32. The reduction gearing comprises a segmental gear 39 mounted on the outer side of the plate 32 by means of a pin 40 for rocking movement in a vertical plane and 20 having teeth 41 meshing with a worm 42 rotatably mounted on the plate 32 with its axis extending vertically. In Figures 3, 5, and 6 of the drawings, a stamping or plate 43 is shown as secured to the outer side of the supporting plate 32 and 25 as having vertically spaced longitudinally projecting tongues 44 which extend over the trunnions 45 at opposite ends of the worm in a manner to cooperate with recesses 46 in the supporting plate 32 to provide bearings for supporting the worm. 30 The free ends of the tongues are fashioned to overlap the outer side of the gear segment 39 and serve to maintain the segment in meshing relation with the worm.

The worm is driven in opposite directions to 35 effect the desired rocking movement of the segment 39 by means of an operating shaft 50 rotatably supported in the hub 51 of a housing 52 which is secured to the inner side of the supporting plate 32. The shaft 50, of course, extends at right 40 angles to the axis of the worm and a crown gear 53 is rotatably mounted in the housing and is secured to the shaft 50. The gear 53 is in the form of a cup-shaped stamping having the axial flange formed with teeth 54 arranged in mesh 45 with a pinion 54' secured to the worm 42. A handle 55 of any suitable character may be secured to the inner end of the shaft 50 for rotating the segment 39 through the medium of the 50 worm gearing.

Rocking motion of the segment 39 is transmitted to a straight-line movement of the T-shaped arm 22 by means of the linkage 56. In detail, the linkage 56 comprises a link 57 having one end secured to the segment, as at 58, for rocking movement as a unit therewith and having the free end pivotally connected to a second link 59 intermediate the ends thereof by means of a pin 60. One end of the link 59 is pivotally connected to the transverse portion 24 of the T-shaped arm 22 and the other end 61 of the link is slidably supported on the plate 32. As shown in Figure 7, a pin 62 similar to the pin 29 is secured to the end 61 of the link 59 in a manner 65 to extend inwardly from the link through a longitudinally extending slot 63 formed in the supporting plate 32. One end of the slot 63 is enlarged, as at 64, to provide for inserting the enlarged head 65 of the pin into the slot and the 70 head is maintained in frictional engagement with the plate 32 by means of a frusto-conical washer 66 slidably mounted on the pin 62 at the outer side of the plate 32. The washer 66 is urged into frictional engagement with correspondingly 75

tapered flanges 67 at the opposite longitudinal edges of the slot 63 by means of a spring 68.

The length of the slot is predetermined to provide the required travel of the T-shaped arm 22 to move the panel 12 from its closed position in the window opening to a position out of the window opening into the well 19. By virtue of this slot, the thrust and pull on the window 12 are in the form of a vertical-line thrust applied substantially at the center of the window. As a result, the window panel may be raised with the minimum effort since binding and undue friction are reduced to the minimum.

In some installations, it is desirable to shift the panel 12 fore-and-aft of the body to either provide for obtaining a ventilating opening at the forward edge of the panel 12, or to relieve the friction at the forward edge of the panel 12 on the adjacent structure which, in the present instance, is the division bar 14. Assuming that it is desired to provide a ventilating slot at the forward edge of the glass panel 12 in the uppermost position of the latter, it is essential to effect rearward shifting movement of the panel 12 after the latter has been raised to its position in the window opening and to return the panel to its normal position by shifting the same forwardly during initial downward movement of the panel 12. This result may be accomplished with my improved regulator mechanism by inclining the rear portion of the slot 63' in the manner clearly shown in Figure 10. The arrangement is such that when the panel 12 substantially assumes its uppermost position in the window opening, the pin 62 is guided in an upward direction by the inclined portion 70 of the slot 63'. Inasmuch as the pin 62 is secured to the link 59 and in view of the fact that the latter is connected to the arm 22, it follows that upward movement of the pin in the inclined portion of the slot 70 effects a pivotal movement of the arm 22 about the pin 29 in a direction to move the forward edge of the panel 12 rearwardly. On the other hand, when the panel 12 is initially lowered, the pin 62 travels downwardly in the inclined portion of the slot toward the horizontal portion 72 and, in so doing, effects a shifting movement of the panel 12 in a forward direction to its original position relative to the window opening.

Thus, from the foregoing, it will be observed that I have provided a relatively simple and inexpensive window regulating mechanism so constructed that the thrust or pull on the window 55 is in the form of a vertical-line thrust applied substantially at the center of the window. It will also be noted that all of the various parts of the window regulating mechanism, including the T-shaped arm 22 and track 30, form an assembly 60 with the supporting plate 32. This feature not only simplifies manufacture, but appreciably expedites assembly and installation. In addition, it will be noted that the regulating mechanism may also be advantageously used in assemblies 65 where it is desired to shift the vertical sliding panel fore-and-aft of the body.

What I claim as my invention is:

1. A window regulator for vehicle bodies having a vertically movable closure panel, comprising a mounting plate fixed to the body structure and having a slot therethrough, a member secured to the lower edge of the closure panel and extending downwardly therefrom, a track fixed against movement with the closure panel and extending vertically, a follower secured to the lower end of the member and engageable with the track, a link having one end pivotally connected to the member adjacent the lower edge of the panel and having means at the opposite end extending through the slot in the mounting plate, and means supported for rocking movement about an axis extending transversely of the path of travel of the panel and connected to the link intermediate the ends thereof for raising and lowering the panel, said slot having a portion extending in a direction fore-and-aft of the body and having another portion extending at an angle to the portion aforesaid and effective to exert a camming action on the link causing the member to swing about the point of engagement of the follower with the track and thereby effect a shifting movement of the panel in a direction fore-and-aft of the body.

2. A window regulator for vehicle bodies having a window opening and a vertically movable closure for said opening, said regulator comprising a guide extending in the direction of sliding movement of the closure and fixed against movement with the closure, a member secured to the bottom of the closure and extending downwardly from the latter, a slideable pivotal connection between the member and guide effective to permit swinging the closure in the plane of the window opening about said connection, and means for raising and lowering the closure having provision for swinging the closure about said connection at one point in the vertical travel of the closure.

3. A window regulator for vehicle bodies having a vertically movable closure panel, comprising a mounting plate, a member secured to the lower edge of the closure panel and extending downwardly therefrom, a track fixed to the mounting plate and extending vertically, a follower secured to the member adjacent the lower end of the latter and engageable with the track, a link having one end pivotally connected to the member adjacent the lower edge of the panel and having a sliding connection at the opposite end with the mounting plate, means supported for rocking movement about an axis extending transversely of the path of travel of the panel and connected to the link intermediate the ends thereof for raising and lowering the panel, and means cooperating with the link and mounting plate effective to swing the closure panel in the plane of the window opening about the point of engagement of the follower with the track.
